(57) **CLAIM**

The ornamental design for a fishing line guide tool, as shown and described.

DESCRIPTION

FIG. 1 is a perspective view of a fishing line guide tool according to a first embodiment;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof;

FIG. 8 is a perspective view of a second embodiment;

FIG. 9 is a top view thereof;

FIG. 10 is a bottom view thereof;

FIG. 11 is a right side view thereof;

FIG. 12 is a left side view thereof;

FIG. 13 is a front view thereof;

FIG. 14 is a rear view thereof;

FIG. 15 is a perspective view of a third embodiment;

FIG. 16 is a top view thereof;

FIG. 17 is a bottom view thereof;

FIG. 18 is a right side view thereof;

FIG. 19 is a left side view thereof;

FIG. 20 is a front view thereof;

FIG. 21 is a rear view thereof;

FIG. 22 is a perspective view of a fourth embodiment including symbolic break lines;

FIG. 23 is a top view thereof;

FIG. 24 is a bottom view thereof;

FIG. 25 is a right side view thereof;

FIG. 26 is a left side view thereof;

FIG. 27 is a front view thereof; and,

FIG. 28 is a rear view thereof.

The space between the symbolic break lines in FIGS. 22, 23, 24, 25, and 26 forms no part of the claimed design.

1 Claim, 28 Drawing Sheets
